UNITED STATES PATENT OFFICE.

WILLIAM E. BUSER, OF CHILLICOTHE, OHIO.

TUFTING-MACHINE.

SPECIFICATION forming part of Letters Patent No. 726,400, dated April 28, 1903.

Application filed May 1, 1902. Serial No. 106,535. (No model.)

To all whom it may concern:

Be it known that I, WILLIAM E. BUSER, a citizen of the United States, residing at Chillicothe, in the county of Ross and State of Ohio, have invented new and useful Improvements 5 in Tufting-Machines, of which the following is a specification.

My invention relates to improvements in tufting-machines for upholstering purposes, 10 and pertains to an improved button-holder, all of which will be fully described herein-after.

My improved button-holder consists of a yielding or elastic tube composed of rubber, 15 which is adapted to receive and to firmly support the button in an upright position and is adapted to be constructed to receive buttons having heads of various sizes and is also capable of being reversed.

20 My rubber yielding or elastic button-holder has many advantages over the wood or metal button-holders heretofore used, among which may be mentioned that the yielding or elastic tube does not in any manner injure the 25 heads of the buttons, owing to its elastic and yielding nature; that owing to its elastic and yielding nature it will not injure the finest fabric, which the spring and wood button-holders now in use frequently do, and especially 30 in connection with the machines in common use where the cloth is pressed tightly downward by means of screws, in which event the metal and wood button-holders now in use frequently cut holes in the fabric or 35 cloth and also frequently destroy or injure the heads of the buttons; in that my improved button-holder will not split or break, as do the wood and metal button-holders now in use; in that the moldboard containing my 40 improved yielding or elastic tubular button-holders can be turned upside down for the purpose of cleaning the cells of the moldboard from the accumulation of chaff or refuse from the tow or filling without any possibility 45 of injury to the yielding or elastic button-holders, whereas with the wooden or spring-metal button-holders in common use they will be injured by turning the moldboard upside down against a trestle or the floor, and 50 in that my elastic or yielding tubular button-holders are adapted to be readily removed or reversed, as may be desired.

In the accompanying drawings, Figure 1 is a perspective view of a portion of a mold-

board, showing my improved button-holder 55 applied thereto. Fig. 2 is an enlarged detached perspective view of one of my button-holders, showing a button in position therein. Fig. 3 is a similar view with the button removed. Fig. 4 is an enlarged vertical sectional view of one of my button-holders used in connection with a shouldered supporting-pin. Fig. 5 is a similar view showing the button-holder upon a straight supporting-pin. Fig. 6 is a detached view of a modification of 65 my tubular yielding or elastic button-holder, in which case it is not provided with any slits to adapt it to receive buttons of various sizes.

Referring now to the drawings, 1 indicates a moldboard having the usual pockets 2. At 70 the intersection of the walls of these pockets are arranged button-holders. My invention pertains to an improved button-holder, which I will now explain.

My improved button-holder consists, generally speaking, of a yielding or elastic tube 4, composed of yielding compressible material, such as rubber. This elastic tube 4 is supported by a suitable pin 5, which has its lower end firmly attached in any desired manner to the bottom of the moldboard, and the pin extends upward into the elastic or yielding tube, as clearly illustrated, and forms a support therefor. These tubes project above the upper end of the supporting-pin to form 85 a yielding or elastic button-receiving recess 7, into which the heads of the buttons 8 are inserted. The pins which support the yielding or elastic tubes may be provided with shoulders 9, upon which the lower ends of the 90 tubes rest, or the pins may be straight, as illustrated in Fig. 5, and in which event the tubes are made sufficiently long to have their lower ends rest directly upon the moldboard and to have their upper ends extend beyond 95 the ends of the supporting-pins to provide yielding and elastic button-receiving recesses. These yielding or elastic tubes which constitute the button-holders are adapted to be removed from the pin for any desired purpose 100 and are therefore adapted to be reversed should their button-receiving ends become worn in any manner, making it desirable to reserve the tubes, and thereby obtaining double the life thereof. If desired, these tubes 105 may be loose upon the pins, since they fit them snugly and will be held by frictional contact, or they can be attached by means

of small nails 10, which nails can be readily drawn when it is desired to remove the elastic or yielding tubes or when it is desired to reserve them. Thus it will be seen that by 5 constructing the button-holders of removable and reversible tubes a desirable construction is provided, and by constructing the tubes of yielding or elastic material they will not damage the heads of the buttons, as do the wooden 10 or metal button-holders now in common use.

As is well known, the cloth is forced down tightly around the button-holders under a severe pressure, and in practice where the usual metal spring or wooden button-holders 15 are used they are practically rigid and frequently punch holes in the fabric. By using button-holders consisting of a yielding or elastic material, such as a tube, they will not injure or mar the most delicate fabric and 20 are adapted to yield and conform to the desired position to prevent injury to the cloth or fabric, while at the same time they serve to support the buttons firmly in an upright position. Also by forming the button-holders 25 of yielding or elastic tubes, as here shown and described, the moldboard can be turned upside down upon a trestle or upon the floor for the purpose of cleaning the pockets and recesses of the button-holders without danger of injuring in any manner the button-holders, as will be readily understood, while 30 injury is likely to occur to a moldboard having button-holders constructed of wood or metal springs. Owing to this fact the moldboard with the usual wooden or metal button-holders cannot be turned upside down for the purpose of cleaning them, thus making 35 it difficult to clean the accumulated chaff or refuse from the tow or filling from the recesses of the moldboard. It is only necessary to turn my moldboard upside down, which is quickly accomplished, and to therefore quickly clean the moldboard without any danger of injury to the button-holders.

40 For the purpose of adapting my button-holders to receive buttons with heads of various sizes they may be provided with a plurality of slits 12, preferably four in number, which will increase the yielding capacity of 45 the button-holders, and therefore adapt them to receive buttons having heads of various sizes. Either one or both ends of the tubes may be so slitted, as will be readily understood. Where the button-holders are to be 50 adapted to receive buttons with heads of various sizes and are also adapted to be reversed, preferably both ends of the tubes will be thus slitted for accomplishing the desired purpose.

55 My button-holders being composed of yielding or elastic tubing will not split or break from use, as do frequently the metal and wooden button-holders now in use.

It will also be noted that my improved button-holders are composed of a combination of 60 rubber *a* and cloth *b*, which make them practically indestructible and at the same time

sufficiently elastic or yielding to receive the button-heads and to support the buttons firmly and to prevent injury to the cloth or 70 fabric.

In addition to the advantages in the use of my tubular yielding or elastic button-holders they are cheap to construct, as well as effective and advantageous, for the reasons al- 75 ready explained.

Having thus described my invention, what I claim, and desire to secure by Letters Patent, is—

1. A tufting button-holder comprising a 80 member having a recess provided with a wall composed of a compressible and yielding material, and a supporting member therefor.

2. In a tufting-machine, a button-holder composed of a tubular rubber member, and 85 a supporting-pin therefor.

3. In a tufting-machine, a removable rubber tubular button-holder, and a supporting-pin therefor.

4. In a tufting-machine, a tubular button- 90 holder having both ends yielding, whereby it is reversible, and a supporting-pin therefor.

5. In a tufting-machine, a button-holder comprising a supporting-pin, and a tubular member surrounding the pin and having a 95 rubber portion projecting above the end of the pin to constitute a yielding or elastic button-receiving recess.

6. In a tufting-machine, a button-holder composed of a tubular rubber member pro- 100 vided with longitudinally-extending slits for the purpose of increasing the capacity of the button-receiving recess, and a supporting member therefor.

7. In a tufting-machine, a button-holder 105 consisting of a tube composed of a combination of rubber and cloth, and a supporting-surface for the button-heads.

8. In a tufting-machine, a button-holder consisting of a tube composed of rubber, and 110 having longitudinal slits at opposite ends.

9. In a tufting-machine, a button-holder consisting of a projecting pin, a rubber tube surrounding it and projecting thereabove, the said tube being removable and reversible in 115 respect to the said pin.

10. The combination in a tufting button-holder of a support for the tufting button-heads with a rubber tube surrounding the support and projecting beyond its support- 120 ing-surface.

11. The combination in a tufting button-holder of a support for the tufting button-heads with a rubber tube projecting beyond the supporting-surface, substantially as 125 specified.

In testimony whereof I have hereunto set my hand in the presence of two subscribing witnesses.

WILLIAM E. BUSER.
